UNITED STATES PATENT OFFICE

1,984,391

LIQUID PUMP

Robert S. Bassett, Buffalo, N. Y.

Application December 9, 1931, Serial No. 579,907

3 Claims. (Cl. 221—95)

My invention relates to improvements in liquid pumps which will draw in both liquids and gases through the intake but from which the discharge of liquids only is desired from the outlet. My invention relates particularly to grease pumps for handling automobile transmission and differential grease, which is pumped from small containers which are frequently emptied, with the result that air enters the intake of the pump, the grease in the container having reached a low level near the pump intake.

The object of my invention is to provide a means to separate gases, such as air, from liquids, such as grease, and to discharge liquids only through the main outlet opening, the gases, together with a small amount of grease, being discharged through a secondary opening.

The result of my invention is to provide a practical method for the rapid dispensing of grease directly from a hose without the necessity of filling measuring containers with the grease to assure that air was not being measured together with the grease by the measuring unit, which, in my drawing, is shown as a liquid operated grease meter of the usual type.

A novel feature of my invention is the discharge of the gases back into the grease container so that the small quantities of grease, which pass out with the gases, are automatically returned to the main supply of grease.

Another novel feature of my invention is the construction of the gas discharge tube so that it is not filled with grease throughout its full length. The restriction at the inlet of this tube allows the lower portion of the tube to contain a mixture of air and grease so that when there is suddenly a large quantity of air to be discharged this air can pass through the restriction at the upper end of the tube readily without the necessity of blowing all of the grease out of the lower part of the tube. The short length of the restricted upper end of the tube is a new and novel feature far superior to an ordinary tube having the same inside diameter throughout its length. The exact cross-section of the gas discharge tube, both at the upper neck and at the lower portion, is not important but, preferably, should be in the shape of a square or a circle. The tube as shown is readily bendable to allow easy lining up of the assembly.

In this application the greatest width of the opening at any section taken across the tube will be spoken of as the "width" though, in the case of a circular cross-section, which is the cus-

tomy form, the width, of course, will be the diameter.

In my drawing the figure is a central longitudinal view of my improved liquid pump, showing a section through the pump cylinder and the gas discharge tube, and showing the outside of the liquid operated metering device and discharge piping.

Pump cylinder 1 is within grease container 2 and passes through grease container cover 3 in the usual manner. Driving pinion 4 and rack 5 move piston rod 6 up and down within pump cylinder 1. The exact construction of the pump or liquid circulating device is not restricted to the construction shown but may be of any suitable construction for creating a flow of grease toward the measuring device.

7 is the upper portion of the pump enclosing rack 5. 8 is the beginning of the discharge passage from the liquid circulating device. 9 is a liquid operated meter of the usual type. 10 is the discharge tubing or pipe leading from the liquid meter 9 and may be fitted with a conventional shut-off valve 11, which prevents the hose from draining when the pumping operation is stopped.

Elements 1 to 11 inclusive are all shown of conventional design and are not limited to the exact construction in the drawing.

At the bottom of pump cylinder 1 is a conventional foot valve 12. 13 is a piston engaging the walls of pump cylinder 1 and fitted with valve disc 14 to allow the passage of the liquid past piston 13 in one direction in the usual manner. 19 is the main delivery opening from the pump on which is mounted the liquid operated meter 9.

In the construction shown the pump discharges through an outlet fitting 15, which screws into the upper portion of the pump casing 7. Outlet fitting 15 could have been shown integral with casing 7, as the exact construction on this point is not important, but the construction shown of having fitting 15 as a separate piece would probably be more convenient for most installations.

Gas discharge tube 16 has one end emptying into grease container 2 and the other end projecting into the discharge passage leading from the pump to the meter. 17 is an orifice at the inlet end of gas discharge tube 16. The opening in orifice 17 is smaller in area than the opening in tube 16 at a point below the orifice. 18 is a binding nut to hold tube 16 firmly in place in the usual manner for the construction shown.

When the pump is operated liquid is pumped out of container 2 up and out through discharge

passage 8. When the level of the liquid in container 2 is so low that air or other gases can pass in through foot valve 12, a mixture of liquid and gases is pumped. Meter 9 requires some pressure 5 to operate it so that the pressure in discharge opening 19 is slightly greater than the pressure in discharge tube 10 leading from the meter. There is, of course, practically no pressure above atmospheric pressure within container 2, as container 2 and container cover 3 do not enclose the supply of liquid so tightly as to exclude the admittance of air from outside the container. The pressure at the lower end of gas discharge tube 16 is, therefore, practically atmospheric only and, 10 therefore, somewhat lower than the pressure at delivery opening 19. This causes a flow of liquid downward through tube 16 at all times. As the inside of tube 16 is considerably larger than the opening in orifice 17, the liquid, which enters 15 through the orifice does not completely fill tube 16, but runs down one side of it. Tube 16 below the orifice is, therefore, filled partly with liquid and partly with air. Because of the air within the tube, the pressure within the tube just below orifice 17 is practically the same as the pressure at the lower end of tube 16. If orifice 17 were omitted, the tube would be filled practically solid with liquid when grease is measured, with the result 20 that the pressure at the upper end of tube 16 would be much higher than in the construction provided for by my invention.

When a small quantity of air passes up through the pump and reaches orifice 17 it can readily 30 pass down through the orifice rather than into meter 9 because of this difference in pressure.

In my experiments I have found that there are certain limits to the length of the opening of orifice 17 in proportion to the width of the opening, this proportion being covered in the claims. 35 It can readily be seen that if the restricted neck at the upper end of the tube or the orifice, is too long that the advantage in the difference of pressure, which controls the flow of the air, will be overcome by the friction of the grease which 40 enters the orifice together with the air, this grease forming a seal if the neck is too long.

The exact proportions of the opening in orifice 17, as compared with the area of tube 16, are controlled by the viscosity of the liquid to be 45 handled. With a very thin liquid the necked opening or orifice at the upper end of the tube can approach in size the tube itself. For extremely viscous liquids a large tube must be used together with a smaller orifice to allow the proper 50 movement of the contents of the tube.

Having thus described my invention what I claim as new and desire to secure by Letters Patent is:

1. A dispensing and measuring apparatus for 55 viscous substances, such as grease, comprising a

meter, a container for the grease, a pump having its inlet below the level of grease in said container and its outlet connected to the meter, a discharge line and a discharge nozzle, said pump, meter, discharge line and nozzle being mounted upon said container and connected together so that upon actuation of said pump grease will flow from said container through said meter, discharge line and nozzle in succession, and a bypass having its outlet in said container above the level of grease 5 therein so as to be remote from the inlet to said pump and so that the grease within the container does not obstruct said outlet and having its inlet in the path of the grease between said pump and meter so that air entrained in the stream of grease 10 will be returned to said container above the grease therein, said bypass having a restricted neck section near the bypass inlet, substantially as and for the purpose described.

2. A dispensing and measuring apparatus for 20 viscous substances, such as grease, comprising a meter, a container for the grease, a pump having its inlet below the level of grease in said container and its outlet connected to the meter, a discharge line and a discharge nozzle, said pump, meter, discharge line and nozzle being mounted upon said container and connected together so that upon actuation of said pump grease will flow from said container through said meter, discharge line and nozzle in succession, and a bypass having its 25 outlet in said container above the level of grease therein so as to be remote from the inlet to said pump and so that the grease within the container does not obstruct said outlet and having its inlet in the path of the grease between said pump and meter so that air entrained in the stream of grease 30 will be returned to said container above the grease therein, said bypass having a restricted neck section near the bypass inlet, substantially as and for the purpose described.

3. A dispensing and measuring apparatus for 35 viscous substances, such as grease, comprising a meter, a container for the grease, a pump having its inlet below the level of grease in said container and its outlet connected to the meter, a discharge line and a discharge nozzle, said pump, meter, discharge line and nozzle being mounted upon said container and connected together so that upon actuation of said pump grease will flow from said container through said meter, discharge line and nozzle in succession, and a bypass having its outlet in said container and having its inlet in the path of the grease between said pump and meter so that air entrained in the stream of grease 40 will be returned to said container above the grease therein, said bypass having a restricted neck section near the bypass inlet, substantially as and for the purpose described.

4. A dispensing and measuring apparatus for 45 viscous substances, such as grease, comprising a meter, a container for the grease, a pump having its inlet below the level of grease in said container and its outlet connected to the meter, a discharge line and a discharge nozzle, said pump, meter, discharge line and nozzle being mounted upon said container and connected together so that upon actuation of said pump grease will flow from said container through said meter, discharge line and nozzle in succession, and a bypass having its outlet in said container and having its inlet in the path of the grease between said pump and meter so that air entrained in the stream of grease 50 will be returned to said container above the grease therein, said bypass having a restricted neck section near the bypass inlet, substantially as and for the purpose described.
